UNITED STATES PATENT OFFICE.

CHARLES H. MOORE, OF YONKERS, NEW YORK.

DESIGN FOR THE ORNAMENTATION OF STATIONARY WASH-BOWLS.

SPECIFICATION forming part of Design No. 22,122, dated January 10, 1893.

Application filed October 21, 1891. Serial No. 409,441. Term of patent 7 years.

To all whom it may concern:

Be it known that I, CHARLES H. MOORE, of Yonkers, county of Westchester, and State of New York, have invented, designed, and produced a new and useful Ornamentation for Stationary Earthenware Wash-Bowls or Basins, of which the following is a full and clear description and the drawing a fac-simile.

The figure shows a stationary wash basin.

10 A, is the bowl.

a, is perforations made in the bowl.

A' is the rim of the bowl.

B, is an ornamental border.

15 C, is an ornamentation of an escalloped pattern on the lower part or bottom of bowl.

D, is a projection on the bottom of the bowl.

This design is distinctly adapted to wash basins or bowls adapted to be stationary, and for the outside of the same.

20 The essential feature of my design is lodged

in an escalloped bottom and a border above it between the scallops and the rim of the bowl. The scallops radiate from the under side of the bowl and extend upward toward the rim, broadening as shown at the top. At 25 this point a border of Greek ornamentation is shown displayed on a band between the top of the scallops and the rim. The ornamentation is usually embossed in the ware in order to give the appearance of bas relief.

30

I claim,

The design for the ornamentation of a stationary wash bowl or basin, which consists of the escalloped bottom C, and ornamental band B, herein shown and described.

CHARLES H. MOORE.
